(57) CLAIM

The ornamental design of a storage container as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever. FIG. 1 is a top perspective view of a storage container in an open position.

FIG. 2 is a top perspective view of the storage container in a closed position.

FIG. 3 is a lower perspective view of the storage container in the closed position.

FIG. 4 is a top view of the storage container in the open position.

FIG. 5 is a top view of the storage container in the closed position.

FIG. 6 is a bottom view of the storage container in the closed position.

FIG. 7 is a left view of the storage container in the open position.

FIG. 8 is a left view of the storage container in the closed position.

FIG. 9 is a front view of the storage container in the open position.

FIG. 10 is a front view of the storage container in the closed position; and,

FIG. 11 is a rear view of the storage container in the closed position.

The dash-dash broken lines depict portions of the storage container that form no part of the claimed design.

1 Claim, 10 Drawing Sheets
